(57) **ABSTRACT**

Heat not burn products comprising an encapsulated aerosol generating agent, the encapsulation having the effect of controlling the release of the agent during use of the heat not burn product. The encapsulation will control the timing of the release of the aerosol generating agent during the use of the heat not burn product, to allow greater control of the puff yield. In the case of some aerosol generating agents, the encapsulation may also increase the stability of the agent and/or prevent its migration within the product.

CONTROL OF PUFF PROFILE

RELATED APPLICATIONS

This application is a Continuation of, and hereby claims priority under 35 U.S.C. § 120 to, U.S. patent application Ser. No. 14/505,477 filed Oct. 2, 2014, and entitled “CONTROL OF PUFF PROFILE,” which in turn is a Continuation of and claims priority under 35 U.S.C. § 120 to U.S. application Ser. No. 13/502,331 filed Aug. 3, 2012, (now U.S. Pat. No. 8,893,724 issued Nov. 25, 2014), also entitled “CONTROL OF PUFF PROFILE,” which is the U.S. National Stage of International Application No. PCT/GB2010/051738, filed Oct. 15, 2010, which in turn claims priority to and benefit of British Patent Application No. GB0918129.8, filed Oct. 16, 2009. The entire contents of the aforementioned applications are herein expressly incorporated by reference.

TECHNICAL FIELD

The present invention relates to encapsulated diluents for inclusion in “heat not burn” products.

BACKGROUND

Heat not burn products, which are sometimes also referred to as non-combustion type smoking articles, are being developed as a possible alternative to conventional smoking articles such as cigarettes. The basic principle is that the product heats tobacco to cause the volatilization of the low boiling point components but avoiding pyrolysis or combustion of the tobacco or volatiles (although some charring of the tobacco can occur during normal usage). This volatilization leads to the creation of a vapor which is drawn through the product and is then condensed into an aerosol and inhaled by the user. The volatilized components include water, nicotine, humectants and light volatiles.

SUMMARY

The present invention relates in particular to those heat not burn products which include a heat source and an aerosol generating portion, such as a tobacco rod, from which certain components are vaporized during use. In such products the heat source may be a solid extrusion molded article of a carbonaceous material which is lit to provide the heat for volatilization and, following lighting, continues to smolder and generate heat. In order to avoid burning on contact with the lit heat source, this part of the product may be surrounded by a non-flammable material such as fiberglass, a paper sheet containing glass fibers, a ceramic, or a paper sheet internally lined with a metal foil. The heat not burn products also include an aerosol-generating portion adjacent to the heat source. This portion generally has a cylindrical body similar in external appearance to the tobacco rod of a conventional cigarette. It includes components which are to be volatilized during use. This portion may include tobacco and will often comprise distinct sections having different functions, including a vaporization chamber (for example comprising tobacco and an aerosol generating agent) adjacent to the heat source, and a cooling chamber (for example comprising shredded reconstituted tobacco sheet) further downstream towards the mouth end of the product. A filter or mouthpiece is usually situated at the mouth end of the product and this may comprise, for example, cellulose acetate.

These heat not burn products include aerosol generating agents such as propylene glycol (PG) and glycerol.

One of the primary aims of the heat not burn products is to earn consumer acceptance as an alternative to conventional smoking articles. One approach to achieving this acceptance will depend upon the heat not burn product producing a similar experience to the smoking articles (although it is recognized that it may also or alternatively be possible to achieve acceptance by other means).

An aspect of the experience of smoking a conventional smoking article is the so-called “puff profile”, also referred to as the “puff per puff profile”. This is the amount of total particulate matter yield (mg/cig) in each puff as the smoking article is consumed. The total particulate matter (TPM) delivery of a conventional cigarette is relatively low during the first couple of puffs, but it tends to gradually increase right through to the final puffs. This gives the smoker the sensation of the smoke gradually increasing in strength.

In contrast, for heat not burn products, the puff profile tends to start very weakly before rapidly increasing within the first few puffs. The TPM delivery then decreases until the product is consumed. This is mainly because these products take a few puffs to reach an optimum temperature, after which they give a high yield of aerosol. However, the puff yield can rapidly diminish during usage as the available aerosol generating agent, such as PG, is boiled off and used up. As a result, such heat not burn products are known to have the disadvantage that they tend to have diminished sensory properties towards the end of the product when compared with a conventional cigarette (see FIG. 1).

It is therefore an aim of the present invention to modify the puff profile of heat not burn products, for example, so as to produce a profile which more closely resembles that of a conventional smoking article.

It has been discovered that, although the aerosol generating agents are vaporized during use of the heat not burn product, vaporization of some agents at lower temperatures can cause problems during storage of the products. Specifically, some aerosol generating agents can migrate during storage and subsequently be lost to the atmosphere or interact with other parts of the product such as the surrounding paper wrapper. This may also lead to staining or marking of the product, either by the agent itself or by compounds released from the agent interaction. It is therefore desirable to immobilize the aerosol generating agent within the heat not burn product until it is required.

Furthermore, when aerosol generating agents are included in heat not burn products, there is currently no way of controlling their vaporization and therefore their effect on the puff profile of the product.

The present invention seeks to improve the performance of heat not burn products and overcome the aforementioned problems by controlling the release of aerosol generating agents.

According to a first aspect of the present invention there is provided a heat not burn product comprising an encapsulated aerosol generating agent.

According to a second aspect of the present invention, there is provided the use of an encapsulated aerosol generating agent in a heat not burn product in order to control the puff profile of the product.

BRIEF DESCRIPTION OF THE DRAWINGS

FIG. 1 is graph showing the puff by puff delivery of total particulate matter of a cigarette compared to that of an

Eclipse® (R. J. Reynolds) heat not burn product, both under three different smoking regimes.

FIG. 2 is graph showing the puff by puff delivery of diluent of a cigarette compared to that of an Eclipse® (R. J. Reynolds) heat not burn product.

DETAILED DESCRIPTION

The heat not burn products according to the invention comprise an encapsulated aerosol generating agent, the encapsulation having the effect of controlling the release of the agent during use of the heat not burn product. In a preferred embodiment, the encapsulation will control the timing of the release of the aerosol generating agent during the use of the heat not burn product, to ensure a gradual and sustained release of the aerosol generating agent and thereby allow greater control of the puff yield. In the case of some aerosol generating agents, the encapsulation may also increase the stability of the agent and/or prevent its migration within the product.

The aerosol generating agent is a substance which generates an aerosol upon heating. The aerosol generating agent may be, for instance, a polyol aerosol generator or a non-polyol aerosol generator. It may be a solid or liquid at room temperature, but preferably is a liquid at room temperature. Suitable polyols include sorbitol, glycerol, and glycols like propylene glycol or triethylene glycol. Suitable non-polyols include monohydric alcohols, high boiling point hydrocarbons, acids such as lactic acid, and esters such as diacetin, triacetin, triethyl citrate or isopropyl myristate. Aliphatic carboxylic acid esters such as methyl stearate, dimethyl dodecanedioate and dimethyl tetradecanedioate can also be used as aerosol generating agents. A combination of aerosol generating agents may be used, in equal or differing proportions. Polyethylene glycol and glycerol may be particularly preferred, whilst triacetin is more difficult to stabilize and also needs to be encapsulated in order to prevent its migration within the product.

There may be several factors influencing the stability and migration of aerosol generating agents under ambient conditions. These factors may include hydrophobicity or hydrophilicity, viscosity, saturated vapor pressure at room temperature, boiling point, molecular structure (such as hydrogen bonding or Van der Waals forces) and the absorptive/adsorptive interaction between the aerosol generating agent and the substrate. Some aerosol generating agents will suffer from migration problems to a greater extent than others; for instance, it has been found that triacetin, isopropyl myristate and triethyl citrate are particularly prone to migration and therefore benefit from immobilisation by encapsulation according to the present invention.

Another relevant factor is the loading level of the aerosol generating agent. For instance, if an aerosol generating agent such as glycerol is included in a large amount, migration problems can still be significant.

The aerosol generating agent loading level in the present invention may depend upon the specific agent. The aerosol generating agent may be included in an amount of up to 95% of the weight of the aerosol generating portion.

The product may also contain non-encapsulated aerosol generating agents, however, such unencapsulated aerosol generating agents are preferably only ones that are stable during storage, such as glycerol.

The encapsulated aerosol generating agent is encapsulated in a barrier material, which not only provides hindrance to migration during storage of the heat not In product but allows controlled release of the agent during use.

The barrier material (also referred to herein as the encapsulating material) may be one that melts, decomposes, reacts, degrades, swells or deforms to release the aerosol generating agent at a temperature above room temperature but at or below the temperature reached inside the heat not burn product during use. In embodiments of the invention, the barrier material releases substantial amounts of the aerosol generating agent above 50° C., preferably above 60° C., 70° C., 80° C. or 90° C. The time taken for the aerosol generating agent to be released may be further controlled by the thickness of the barrier material.

The barrier material may be, for example, a polysaccharide or cellulosic barrier material, a gelatin, a gum, a gel, a wax or a mixture thereof. Suitable polysaccharides include 15 alginate, dextran, maltodextrin, cyclodextrin and pectin. Suitable cellulosic materials include methyl cellulose, ethyl cellulose, hydroxyethyl cellulose, hydroxypropyl cellulose, carboxymethyl cellulose, and cellulose ethers. Suitable gums include gum Arabic, gum ghatti, gum tragacanth, 20 Karaya, locust bean, acacia gum, guar, quince seed and xanthan gums. Suitable gels include agar, agarose, carageenans, furoidan and furcellaran. Suitable waxes include carnauba wax.

In a preferred embodiment of the invention, the barrier material comprises a polysaccharide. An alginate is especially preferred, due to its encapsulation properties. The alginate may be, for instance, a salt of alginic acid, an esterified alginate or glyceryl alginate. Salts of alginic acid include ammonium alginate, triethanolamine-alginate, and 30 group I or II metal ion alginates like sodium, potassium, calcium and magnesium alginate. Esterified alginates include propylene glycol alginate and glyceryl alginate.

In an embodiment, the barrier material is sodium alginate and/or calcium alginate. Calcium alginate provides a greater inhibition of migration of the aerosol generating agent at ambient temperature than sodium alginate, but also may release the aerosol generating agent at a higher temperature than the latter.

In another embodiment of the invention, acacia gum is 40 provided as the barrier material for encapsulating triacetin.

In some embodiments, the encapsulated aerosol generating agent may be encapsulated using two or more encapsulating materials, for example in separate layers.

In order to provide the desired timing of the release of the 45 aerosol generating agent, different encapsulation materials may be used or different encapsulation approaches. For example, in order to provide instant release of aerosol generating agent upon lighting of the heat not burn product, the aerosol generating portion may include a stable aerosol generating agent, such as glycerol, in non-encapsulated form, applied directly to the tobacco. For release shortly thereafter, aerosol generating agent may be provided which is encapsulated using a barrier material with a relatively low melting point, a thin barrier layer, and/or a barrier created by 55 mixing the barrier material with which the aerosol generating agent, to provide prompt release as the temperature in the aerosol generating portion of the product starts to rise. Finally, further aerosol generating agent may be provided for delayed release and this agent can be encapsulated using a barrier material with a relatively high melting point, or a relatively thick harder layer, and/or the aerosol generating agent is completely surrounded by the barrier material to delay release until the barrier has been properly compromised.

In some embodiments of the invention, the barrier material, is applied to particulate carrier material (such as a particulate sorbent material) carrying the aerosol generating

agent. This application of the barrier material may be carried out by any suitable method known to the skilled person or described herein, which does not cause complete loss of the aerosol generating agent in the process. Such methods include, for example, spray drying, coextrusion, prilling, etc. Preferably, substantially no aerosol generating agent is lost due to the step of applying the barrier material. In an embodiment, the barrier material, or a precursor thereto is sprayed onto the particulate carrier material.

For instance, the particulate carrier material carrying the aerosol generating agent can be sprayed with an aqueous sodium alginate solution and dried to form a water-soluble film of sodium alginate on the surface. Alternatively, the particulate material can be sprayed with sodium alginate and then treated with a source of calcium ions, to form a water-insoluble film or gel covering of calcium alginate in some embodiments, the calcium ions may already be naturally present.

In the resulting product, individual aerosol generating agent-carrying particles may be surrounded by barrier material and migration of the agent is further hindered under ambient conditions. Alternatively, the agent may be combined with barrier material before application to the carrier, such that in the resulting product the barrier material resides in homogeneous admixture with the agent. In a yet further alternative, the agent may be pre-encapsulated with the barrier material before application to the carrier (and so is not in intimate contact with the carrier). One or any combination of these approaches may be used in the present invention.

In a particularly preferred embodiment, the barrier material used to encapsulate the aerosol generating agent releases the aerosol generating agent in a temperature-dependent manner. This may be achieved by using a barrier material which has a melting point which is such that the encapsulated agent will be released when it is exposed to a given temperature during normal use of the heat not burn product.

In order to provide control of the release of the aerosol generating agent over the whole period of the use of the heat not burn product, the encapsulated aerosol generating agent will preferably gradually release the aerosol generating agent, rather than allowing all of the agent to be released at the same time. In one embodiment of the invention, this is achieved by using more than one barrier material, the materials having different melting points. Capsules made from material with the lower melting points will release their aerosol generating agent before the capsules made from material with higher melting points. In another embodiment, the barrier material is used to form capsules with different wall thicknesses, the thicker walls taking longer to melt and release the aerosol generating agent than thinner walls. In such an embodiment, one or more different encapsulating materials may be used. In a yet further embodiment, the positioning of the encapsulated aerosol generating agent within the product may help to control the timing of release, especially where there tends to be a temperature gradient along the length of the heat not burn product. Positioning the encapsulated agent along the length of the tobacco rod of the product may allow the timing of the release of the aerosol generating agent to be controlled, with the release being spread over the whole period of use of the product, the encapsulated agent positioned closer to the heat source being released first and that positioned closest to the mouth end of the product being released later.

In a different approach, the encapsulating material is frangible and the release of the aerosol generating agent is manually controlled by the consumer who must crush and

rupture one or more capsules to enhance the yield. This gives the consumer control over the puff profile of the product.

This use of encapsulated aerosol generating agent in a heat not burn product can be used to achieve any desired puff profile as measured on a smoke engine. Thus, the heat not burn product could be designed to mimic the profile of a conventional cigarette, with a gradual increase in the yield with every puff. Alternatively, the puff profile could be designed to be much flatter, with a consistent yield throughout the consumption of the product.

In some embodiments of the invention, further components may be encapsulated together with the aerosol generating agent, for example other diluents and/or flavorants. Such further components may also or alternatively be included in the heat not burn product in separate capsules.

The inclusion of flavorants which are released together with the aerosol generating agent may be particularly attractive, as the perception of a reduction in flavor by the user will accompany a reduction in the aerosol generating agent being released, which in turn indicates that the product is finished.

In preferred embodiments of the present invention, the heat not burn product comprises a heat source and an aerosol generating portion which made up of discrete sections comprising tobacco, in some embodiments, the discrete sections include different amounts of encapsulated aerosol generating agent or different types of encapsulated aerosol generating agent. For example, more encapsulated material may be present in sections closer to the mouth end of the product than those closer to the heat source. Alternatively, the nature of the aerosol generating agent and/or or the nature of the barrier material may differ in the different sections of the aerosol generating portion of the product, in order to contribute to the control of the release of the aerosol generating agent during use of the product.

Migration of the aerosol generating agent between different parts of the heat not burn product (for example, between adjacent tobacco sections) will be avoided by encapsulation and this will help to ensure that the product produces predictable and reproducible results, even when relatively unstable aerosol generating agents, such triacetin, are used.

Although the foregoing detailed description focuses on the inclusion of the encapsulated aerosol generating agent in a particular type of heat not burn product, it is suitable for inclusion in other types of heat not burn products.

EXAMPLES

50 Triacetin (a compound widely understood to be a smoke diluent) was encapsulated in acacia gum a using a spray drying technique to give a fine powder with a mean particle size (D_v) of 53 μm . The resulting capsules were further coated with low viscosity sodium alginate using a fluidized bed technique. The particles were then treated with calcium 55 chloride to crosslink the alginate and improve its barrier properties. The resulting capsules had a mean particle size (D_v) of 610 μm , a tapped density of 410 g/liter and a triacetin content of 17.0% by weight. These capsules were designated as capsule 1.

60 A second batch of encapsulated triacetin was made using a different method. Triacetin was encapsulated in carnauba wax using a spray chilling (paling) technique. The resulting capsules had a mean particle size (D_v) of 438 μm and a triacetin content of 20.4% by weight. These capsules were designated as capsule 2.

Eclipse cigarettes (by R J Reynolds Tobacco) are "heat-not-burn" products that use the heat from the combustion of

a plug of carbon to vaporize a smoke diluent (glycerol) to form a smoke-like aerosol for inhalation. There are two distinct types of tobacco in Eclipse cigarettes; a section containing high levels of diluent close to the combustible carbon at the lit end and a second section at the mouth end that does not contain the diluent. A large percentage of the smoke from Eclipse cigarettes is made up of glycerol.

Using Eclipse cigarettes, a window was cut through the tobacco wrapper into the front tobacco section (nearest to the lit end) and approximately 130 mg of tobacco was removed. The tobacco was replaced with approximately 235 mg of capsule 1. The window in the tobacco wrapper was then closed by folding back the tobacco wrapper and the incision sealed using glue and a conventional cigarette paper. A second window was cut through the tobacco wrapper into the rear tobacco section (nearest to the mouth end) and approximately 150 mg of tobacco was removed. The tobacco was replaced with approximately 196 mg of capsule 6. The window in the tobacco wrapper was then closed by folding back the tobacco wrapper and the incision sealed using glue and a conventional cigarette paper.

15 15 cigarettes were prepared with capsules and were smoked on a Borgwaldt RM20D smoking engine under and intense smoking regime (a 55 mL puff of 2 second duration, every 30 seconds with the tip ventilation blocked). Total particulate matter was collected on Cambridge Filter Pads on a puff by puff basis. The filter pad was analyzed for triacetin.

For comparison, unmodified Eclipse cigarettes were smoked under the same regime on a puff by puff basis and the filter pads analyzed for glycerol.

The results (shown in FIG. 2) indicate that glycerol from the unmodified control cigarette enters the mainstream smoke from puff one and rapidly increases after puff two. In contrast, the encapsulated triacetin does not enter the mainstream smoke in substantial quantities until puff four and the rate of release to the smoke is lower when compared with glycerol. This demonstrates a controlled release of diluent to the mainstream smoke.

The invention claimed is:

1. A heat not burn product comprising:

an encapsulated aerosol generating agent, wherein the release of the aerosol generating agent during use of the product is gradual and sustained, controlled using different encapsulation materials or different encapsulation approaches to produce a desired puff yield of total particulate matter,

wherein the aerosol generating agent is selected from sorbitol, glycerol, propylene glycol, triethylene glycol, lactic acid, diacetin, triacetin, triethyl citrate, isopropyl myristate, methyl stearate, dimethyl dodecanedioate and dimethyl tetradecanedioate, and

wherein the encapsulation materials are selected from alginate, dextran, maltodextrin, cyclodextrin, pectin, methyl cellulose, ethyl cellulose, hydroxyethyl cellulose, hydroxypropyl cellulose, carboxymethyl cellulose, cellulose ethers, gelatin, gum Arabic, gum ghatti, gum tragacanth, Karaya gum, locust bean gum, acacia gum, guar gum, quince seed gum, xanthan gums, agar gel, agarose gel, carrageenan gel, furoidan gel and furcellaran gel, carnauba wax, or a mixture thereof.

2. A product as claimed in claim 1, wherein the aerosol generating agent is encapsulated using two or more different encapsulation materials, the encapsulation materials having different melting points.

3. A product as claimed in claim 2, wherein at least one of the encapsulation materials is a polysaccharide and is at least one of alginate, dextran, maltodextrin, cyclodextrin or pectin.

5 4. A product as claimed in claim 2, wherein at least one of the encapsulation materials is a cellulosic barrier material and is at least one of methyl cellulose, ethyl cellulose, hydroxyethyl cellulose, hydroxypropyl cellulose, carboxymethyl cellulose, or cellulose ethers.

10 5. A product as claimed in claim 2, wherein at least one of the encapsulation materials is a gum and is at least one of gum Arabic, gum ghatti, gum tragacanth, Karaya gum, locust bean gum, acacia gum, guar gum, quince seed gum or xanthan gum.

15 6. A product as claimed in claim 2, wherein at least one of the encapsulation materials is a gel and is at least one of agar, agarose, carrageenans, furoidan or furcellaran.

7. A product as claimed in claim 2, wherein the aerosol 20 generating agent is carried by a particulate carrier material and at least one of the encapsulation materials is applied to the carrier material carrying the aerosol generating agent.

25 8. A product as claimed in claim 1, wherein the aerosol generating agent is encapsulated using different thicknesses of encapsulation material, the thickness of the encapsulation material determining when the aerosol generating agent is released during use of the product.

9. A product as claimed in claim 1, wherein the distribution 30 of the encapsulated aerosol generating agent within the heat not burn product controls the timing of the release of the aerosol generating agent during use of the product.

10. A product as claimed in claim 1, wherein the aerosol generating agent is a polyol.

11. The product as claimed in claim 10, wherein the 35 polyol is at least one of sorbitol, glycerol, or a glycol.

12. The product as claimed in claim 11, wherein the polyol is a glycol, and wherein the glycol is at least one of propylene glycol or triethylene glycol.

13. The product as claimed in claim 1, wherein the aerosol 40 generating agent is a non-polyol.

14. The product as claimed in claim 13, wherein the non-polyol is at least one of an acid, an ester, or an aliphatic carboxylic acid ester.

15. The product as claimed in claim 14, wherein the 45 non-polyol is an acid, and wherein the acid is lactic acid.

16. The product as claimed in claim 14, wherein the non-polyol is an ester, and wherein the ester is at least one of diacetin, triacetin, triethyl citrate or isopropyl myristate.

17. The product as claimed in claim 14, wherein the 50 non-polyol is an aliphatic carboxylic acid ester, and wherein the aliphatic carboxylic acid ester is at least one of methyl stearate, dimethyl dodecanedioate or dimethyl tetradecanedioate.

18. A product as claimed in claim 1, wherein the aerosol 55 generating agent is released during use of the heat not burn product so as to provide a substantially constant delivery of total particulate matter per puff.

19. A product as claimed in claim 1, wherein the aerosol generating agent is released during use of the heat not burn product so as to provide a gradually increasing delivery of total particulate matter per puff.

20. A method comprising: incorporating an encapsulated aerosol generating agent in a heat not burn product, wherein the aerosol generating agent is encapsulated using different encapsulation materials or different encapsulation approaches, in order to control the gradual and sustained release of the

9

aerosol generating agent, so as to produce a desired puff yield of total particulate matter,
 wherein the aerosol generating agent is selected from sorbitol, glycerol, propylene glycol, triethylene glycol, lactic acid, diacetin, triacetin, triethyl citrate, isopropyl myristate, methyl stearate, dimethyl dodecanedioate and dimethyl tetradecanedioate, and
 wherein the encapsulation materials are selected from alginate, dextran, maltodextrin, cyclodextrin, pectin, methyl cellulose, ethyl cellulose, hydroxypropyl cellulose, carboxymethyl cellulose, gum Arabic, gum ghatti, gum tragacanth, Karaya gum, locust bean gum, acacia gum, guar gum, quince seed gum, xanthan gums, agar gel, agarose gel, carrageenan gel, furoidan gel and furcellaran gel, carnauba wax, or a mixture thereof.

21. A method for controlling the gradual and sustained release of an aerosol generating agent, so as to produce a desired puff yield of total particulate matter, in a heat not burn product, the method comprising:

10

including in the heat not burn product an encapsulated aerosol generating agent, wherein the encapsulated aerosol generating agent is encapsulated using different encapsulation materials or different encapsulation approaches,

wherein the aerosol generating agent is selected from sorbitol, glycerol, propylene glycol, triethylene glycol, lactic acid, diacetin, triacetin, triethyl citrate, isopropyl myristate, methyl stearate, dimethyl dodecanedioate and dimethyl tetradecanedioate, and

wherein the encapsulation materials are selected from alginate, dextran, maltodextrin, cyclodextrin, pectin, methyl cellulose, ethyl cellulose, hydroxypropyl cellulose, carboxymethyl cellulose, gum Arabic, gum ghatti, gum tragacanth, Karaya gum, locust bean gum, acacia gum, guar gum, quince seed gum, xanthan gums, agar gel, agarose gel, carrageenan gel, furoidan gel and furcellaran gel, carnauba wax, or a mixture thereof.
